J. F. HEALY

TROLLEY CONSTRUCTION

Filed May 25, 1921

UNITED STATES PATENT OFFICE.

JAMES F. HEALY, OF CHICAGO, ILLINOIS.

TROLLEY CONSTRUCTION.

Application filed May 25, 1921. Serial No. 472,494.

To all whom it may concern:

Be it known that I, JAMES F. HEALY, a citizen of the United States, residing at Chicago, in the county of Cook and State 5 of Illinois, have invented new and useful Improvements in Trolley Construction, of which the following is a specification.

This invention relates to trolley cars, and its object is to provide a trolley of novel 10 construction, which is positive in action and eliminates the difficulties usually found in the handling of the trolley.

In order that the invention may be better understood, reference is had to the accompanying drawing forming a part of this specification, in which

Fig. 1 is an elevation of the novel trolley as applied to the rear end of a car;

Fig. 2 is an enlarged vertical section of 20 the mechanism at the base of the trolley;

Fig. 3 is an elevation of the upper end of the trolley; and

Fig. 4 is a plan view of the showing in Fig. 2.

Referring specifically to the drawing, 5 denotes the rear portion of a typical trolley car, 6 the overhead current wire, 7 the trolley pole, 8 the trolley wheel, and 9 the usual turntable at the base of the pole. The 10 spring assembly associated with the turntable, and serving to throw the trolley pole upwardly, is now done away with, the present equivalent being a mechanism operated by compressed air.

On the turntable is mounted a cylinder 10, which is adapted to receive air under pressure from the brake-service storage tank of the car by way of a supply pipe 11 entering the cylinder 10 at 12, and provided

40 with a rotary shut-off valve 13. At that end of the cylinder which is supplied with air as just stated is located a release valve 14 of the spring-seated poppet type; and also an automatic pressure-regulating valve 15

45 of any approved type, to maintain a pre-determined pressure of air in that end of the cylinder which is under consideration. Due to the necessary motion of the turntable, 9, a swivel coupling 16 of suitable 50 construction is interposed in the supply pipe 11 at the point of its junction with the turntable.

The lower part of the trolley pole 7 terminates in proximity to the aforesaid end 55 of the cylinder, in the form of a fork 17, whose branches are pivoted in ears 18, up-

standing from the turntable to enable the pole to swing in a vertical plane. At the shoulders of the fork are pivoted, as shown at 19, the ends of two arms 20, which 60 extend alongside the cylinder in the direction of its opposite end. The free ends of the arms 20 are connected across by a bar 21. Within the cylinder is a piston 22, whose operating rod 23 extends to meet the 65 bar 21 in the form of a loose connection 24 at the middle of the bar.

The release valve 14 of the cylinder and the shut-off valve 13 of the air-supply pipe are controlled jointly by a rocker arm 25 70 fulcrumed in a bearing 26 carried by the cylinder. When the arm 25 is rocked it pushes the valve 14 open, and turns the valve 13 shut through a gear-sector-and-pinion arrangement 27. The valve 14 is therefore 75 closed, and the valve 13 open, normally.

From the sector at 27 a cord or light cable 28 is led upwardly alongside the trolley pole 7 to a point near the upper extremity thereof. As shown in Fig. 3, the 80 part that carries the trolley wheel 8 is made separate from the pole in the form of a rocker arm 29 positioned alongside the pole, and fulcrumed at 30 in the end of the same. The inner section of the arm is dropped 85 somewhat to permit a leaf spring 31 to be interposed between it and the pole with a tendency to swing the section on the pole, the spring being secured with one end to the pole. The free end of the said section receives the upper end of the cord or cable 28, 90 the latter being passed through suitable guides 32 and trained over a small pulley 33.

In operation, the pressure of the air supplied to the cylinder 10 serves, through the agency of the piston 22, rod 23, bar 21 and side arms 20, to draw the trolley pole upwardly so as to press the wheel against the wire for running service. This pressure renders the cord or cable 28 slack, so as to be without function. Now, should the trolley wheel become separated from the current wire on account of slippage, the breaking of the wire, or the striking of an obstruction 100 in the same, the trolley would not swing up to and remain in a vertical position, as is usually the case with spring-actuated trolley poles, but would rise slightly and then drop to the roof of the car within handy 105 reach. This action would be due to the deflection of the rocker arm 29 on account of 110

its release from the current wire. The rocking of the arm would thus draw, through the cord or cable 28, upon the rocker arm 25 so as to release the air in the cylinder and 5 shut off the supply, as described, whereby the pole would drop of its weight.

From that section of the rocker arm 29 which carries the wheel, depends the usual rope 34 for handy access by the conductor.

10 In case the pole is again to be raised, all that is required is a slight pull on this rope, which draws the wheel section back into alinement with the pole. This action restores the slack to the cord or cable 28, causing 15 the supply valve of the cylinder to be opened and the release valve to shut. New air under pressure being admitted, the piston will move outwardly bringing about the ascent of the trolley pole into service position.

20 A structure is thus had which is simple, handy and automatic, and which does not require anyone to climb on top of the car to adjust the trolley in case the pull rope 25 is broken, thus eliminating danger from electric shock. The electrical wiring of the

trolley has not been mentioned, as this is easily applicable by anyone skilled in the art.

30 I claim:—

The combination of a trolley pole having a pivoted section which carries the trolley wheel, a fluid-pressure cylinder, a piston in the cylinder, a connection between the piston and the trolley pole, a valve for admitting fluid-pressure to the cylinder for moving the piston in a direction to elevate the trolley pole, a fluid-pressure exhaust valve, actuating means for the valves whereby the closure of one valve is accompanied by the 40 opening of the other valve, the admission valve being normally open and the exhaust valve being normally closed, a spring engageable with the aforesaid pivoted section of the trolley-pole for normally holding 45 said section in alinement with the pole, and a flexible connection between said pivoted section and the aforesaid actuating means of the valves.

45 In testimony whereof I affix my signature.

50 JAMES F. HEALY.
